UNITED STATES PATENT OFFICE

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,061, dated September 9, 1902.

Application filed July 29, 1902. Serial No. 117,580. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is illustrated in front view.

The leading features of my design consist of a frame the sides and cross-piece of which have a plain border, arranged along which are acorn-like protuberances. At each of the top corners of the frame is shown the representation of an escalloped shell. The cross-piece is in the shape of a hood, with the representation of a censer centrally disposed thereon. Extending oppositely from the censer are vo-

lutes or scrolls, some of the branches of which face inwardly and some outwardly. The center or summer front has a plain border near its outer edges and a central panel, bearing within it the conventionalized representation of an eagle. Springing from the central panel are scrolls of diversified form, and resting on the top of the panel is the typical representation of a crown. Below the summer front and extending for the width thereof is an open-work frame.

I claim—

The ornamental design for a fireplace-front as herein shown and described.

In testimony whereof I have hereunto set my hand.

THOMAS M. DUDGEON.
